ERASER

William H. Hutter, Racine, Wis., assignor to Gertrude Reinke, Chicago, Ill., as trustee

Application September 24, 1930
Serial No. 483,996

5 Claims. (Cl. 120—36)

The present invention relates to erasers, and is particularly concerned with erasers having a reserve supply of eraser material such as rubber, gum or the like, which is capable of being fed outward to renew the eraser after the rubber has been worn down from use.

One of the objects of the invention is the provision of an improved eraser having a reserve supply of erasing material which is conveniently enclosed and protected in a handle or casing but which may be adjusted to renew the eraser as fast as the eraser wears down.

Another object is the provision of a simplified form of securing device for adjustably holding a supply of erasing material in a casing or handle in such manner as to keep the eraser in good condition, to support the working point of the eraser in a most advantageous way, and to permit the readjustment of the erasing material to compensate for the wear due to its use.

Another object is the provision of a renewable eraser which may be readily renewed and trimmed to the desired shape by means of a trimming accessory furnished with the eraser casing.

Another object is the provision of an eraser which is efficient, economical, sturdy, and adapted to be carried about in the pocket of the user after the manner of a fountain pen or other writing and drawing accessories.

Other objects and advantages of the invention will be apparent from the following description and from the accompanying drawing in which similar characters of reference indicate similar parts throughout the several views.

Referring to the single sheet of drawing: Fig. 1 is a front elevational view of the eraser as it appears when completely enclosed.

Fig. 2 is a similar view of the eraser ready for use with the enclosing cap mounted upon the end of the casing.

Fig. 3 is a sectional view taken on the plane of the line 3—3 of Fig. 5.

Fig. 4 is an elevational view of the supply of erasing material and its supporting sleeve.

Fig. 5 is an enlarged sectional view taken on the plane of line 5—5 of Fig. 3, showing the details of the cap and trimming knife.

Fig. 6 is a sectional view taken through the trimming knife on the plane of the line 6—6 of Fig. 5.

The erasers constructed according to the present invention are preferably enclosed in a conveniently portable casing similar to that employed for fountain pens, and consequently the eraser which is indicated in its entirety in Fig.

1, preferably includes a casing member 11, which may be constructed of any ornamental material such as hard rubber, pyrolin, celluloid, metal, phenolic condensation material such as bakelite, or the like.

The casing 11 is preferably substantially cylindrical and provided with an axially extending bore 12, and if desired the end 13 of the casing may be tapered for ornamental reasons and for the purpose of receiving and supporting a cap 14.

The cap 14 is preferably constructed of the same kind of material as the casing 11, and may be provided with a reinforcing metal band 15, and with a spring clip 16 of any convenient type, and adapted to resiliently clamp the eraser to the clothing 70 of the user when the eraser is carried about on the person of the user. The cap 14 is preferably formed with an axially extending bore 17 adapted to receive the tapered working end 18 of the handle 11, and the cap is preferably provided with 75 internal threads 19 adapted to engage complementary threads 20 located adjacent the working end 18 of the handle 11.

Referring to Fig. 4, this is an elevational view of the supporting and reinforcing sleeve 21 for 80 the body 22 of erasing material such as rubber, gum or the like. The body 22 preferably consists of an elongated cylindrical piece of rubber adapted to be slidably received in the sleeve 21 and provided with a working surface or point 23, preferably V-shaped in cross section, that is, the point 23 is beveled off at 24 on two diametrically opposite sides so that the point 23 is substantially wedge shaped and provided with a sharp edge 23.

The sleeve 21 is preferably provided with a shank 25 of reduced size adapted to be slidably received in the bore 12 of the handle 11. The sleeve 21 is also preferably provided with an outer end 26 of greater thickness forming an annular shoulder 27 for determining the final position of the sleeve 21 in the handle 11.

The outer surface of the end 26 of sleeve 21 is preferably flush with the outer surface of casing 11 when the parts are assembled as in Fig. 3, but 100 the sleeve 21 preferably tapers outward from the body to the handle 11, so as to prevent interference between the sleeve 21 and the internal threads 19.

The shank 25 of sleeve 21 is preferably provided with one or more longitudinally extending slots 28 which are adapted to receive elongated prongs 29 having inwardly extending pointed ends 30. The prongs 29 are initially adapted to remain in the position shown in Fig. 4, with the body of 110

the prong projecting outward from the shank of sleeve 25, and the points 30 of the prongs withdrawn from the bore 31 of the sleeve. The bore 31 of the sleeve is adapted to slidably receive the 5 rubber body 22 of erasing material, and permit the ready adjustment of the rubber eraser in the sleeve 21 when the prongs are in the position of Fig. 4.

When the sleeve and rubber eraser are inserted 10 in the handle 11 as shown in Fig. 3, the bodies of the prongs 29 slidably engage the inside of bore 25, and the walls of the casing 11 cam the prongs 29 inward until the points 30 engage in the rubber body 22. The sleeve is held in the handle 11 by frictional engagement of the walls of the sleeve 15 with the walls of the bore 12, and by the friction produced by the resilient prongs 29, but the sleeve may readily be withdrawn by holding the handle in one hand and pulling on the sleeve with the 20 fingers of the other hand.

It will thus be observed that the rubber eraser 22 may be used very conveniently by grasping the handle 11 in any convenient manner and applying the point 23 to the lines, figures, characters or 25 the like which are to be erased.

Furthermore, as the rubber on the eraser inevitably wears down, the sleeve 21 may be drawn out of its casing 11 and the rubber body 22 released by the prongs 30. The rubber body 22 30 may then be readily adjusted in the sleeve 21, and the sleeve and rubber eraser reinserted in the casing 11 where they will be held in the adjusted position, thereby permitting convenient readjustment of the length of the rubber eraser 35 as the rubber wears down.

If desired the amount of rubber projecting from the casing or sleeve can be regulated at any time so that the rubber eraser may be given the maximum amount of support and reinforcement for 40 erasing heavy work, and when the eraser is not in use it may be kept in good condition by enclosing the eraser in the cap 14. The cap 14 is adapted to be supported upon the tapered end 13 of the casing 11 when the eraser is in use, or 45 the cap may be removed entirely.

In order to provide for the trimming of the working point of the eraser, the cap 14 is preferably provided with a plug 32 which is seated in the bore 17 of the cap 14 and which closes 50 the open end 33 of the type of cap shown in Fig. 5. The plug 32 preferably has an annular flange 34 for engaging the end of cap 14 and fixedly supported in the plug 32 is a trimming and erasing knife 35.

The knife 35 comprises a sheet metal member 55 preferably formed of tool steel or other material capable of maintaining a sharp working edge, and the knife is preferably formed with a pair of flanges 36, 37 joined together at their apex 38 to form a knife point which is substantially V-shaped in cross section. The outer edges 39 of the knife 35 are preferably beveled and sharpened from the outside and the edges 39 are 60 preferably also beveled downward from the point 40 as shown in Fig. 5, thereby providing a knife point which is adapted to produce a shearing action when the point 40 is pressed downward upon the rubber body 22. It will be evident that the 65 knife 35 is peculiarly adapted to form the working point 23 in the rubber 22, as shown in Fig. 4, and the present eraser is thus provided with a trimming knife which is adapted to be used to maintain the point of the eraser in the most desirable working condition.

The end of the cap 14 is preferably provided

with external threads 41 and an auxiliary tip or cap 42 is preferably provided having an axially extending bore 43 for receiving and enclosing the knife 35, the auxiliary cap 42 having threads 44 complementary to the threads 41 on the cap 14.

It will thus be observed that the knife 35 may also be used for particularly difficult erasures where it is necessary to remove some of the body of the paper or ink after which the cap 14 may be removed and the erasing conveniently finished by the use of the rubber 22.

The present eraser is capable of use for a long period of time and provides a convenient erasing accessory which should form a part of every 90 fountain pen set or set of drawing equipment. The supply of erasing material such as rubber or gum may be readily fed outward as desired and when the rubber has been worn out it may be replaced with a new rubber eraser of the same 95 form which may be conveniently trimmed and maintained in good condition by the trimming knife located in the cap.

While I have illustrated and described a specific embodiment of my invention, many modifications may be made without departing from the spirit of the invention, and I do not wish to be limited to the precise details set forth but desire to avail myself of all changes within the 100 scope of the appended claims.

Having thus described my invention, what I claim is new and desire to secure by Letters Patent of the United States is:

1. In a renewable eraser device, the combination of an elongated body member having an 110 elongated receptacle formed therein, with an open ended metallic member adapted to be slidably mounted in said receptacle to determine the position of an eraser body in said receptacle, a shoulder carried by said metallic member for 115 determining the position of said metallic member in said receptacle, and a resilient prong member carried by said metallic member and normally urged toward a position outside the metallic member, said prong adapted to be forced 120 into an eraser body by engagement of said metallic member with the walls of said receptacle.

2. In a renewable eraser device, the combination of an elongated body member having a bore 125 formed therein for receiving an eraser body, with an open ended metal sleeve adapted to be slidably mounted in said bore to determine the position of an eraser body in said bore, said sleeve having an annular shoulder for engaging the end of said body member and said sleeve having a longitudinally extending integral prong formed out of its body, said prong being resiliently urged into a position outside the metal sleeve, said prong 130 adapted to be forced into an eraser body by engagement of said metal sleeve with the walls of said receptacle when said shoulder engages the end of said body member.

3. An eraser holder comprising a casing open at one end, an eraser holding casing adapted to telescope therein comprising an enclosure open at both ends and having rigid walls for receiving and enclosing a rubber eraser therein, and a flexible finger formed on one of the walls of said eraser holding casing adapted to be flexed into clamping engagement with the eraser through engagement thereof with the wall of the casing.

4. An eraser holder comprising a casing open at one end, an eraser holding casing adapted to telescope therein comprising an enclosure open at both ends and having rigid walls for receiving and

enclosing a rubber eraser therein, a finger cut from the metal wall of said eraser holding casing so as to freely flex with respect thereto, and an inwardly extending projection formed on the free end of said finger adapted to be forced into the eraser by the first mentioned casing upon the second mentioned casing being telescoped therein, said finger being adapted to spring outwardly therefrom upon said second mentioned casing

being removed so as to permit adjustment of the eraser while the same is retained therein.

5. An eraser holder comprising a casing and a sleeve to embrace a rubber eraser insertible in said casing and having eraser engaging means in the form of a depressible inwardly hooked finger operable upon the insertion of said sleeve in said casing to prevent an eraser from moving therein. 80
